UNITED STATES PATENT OFFICE.

JOHN A. MILLER, OF ST. CHARLES, MISSOURI.

COMBINED WRENCH AND DRILL.

SPECIFICATION forming part of Letters Patent No. 253,549, dated February 14, 1882

Application filed June 7, 1881. (No model.)

To all whom it may concern:

Be it known that I, JOHN A. MILLER, of St. Charles, Missouri, have made a new and Improved Combined Wrench and Drill, of which 5 the following is a full, clear, and exact description, reference being had to the annexed drawings, making part of this specification, in which—

Figure 1 is a side elevation of the wrench; 10 Fig. 2, an edge elevation of the wrench; Fig. 3, an elevation similar to that of Fig. 2, but showing the plate used in fastening the wrench proper in the holder turned up; Fig. 4, a side elevation of the wrench, the fastening-plate 15 being upturned; Fig. 5, an elevation of the combined wrench and drill; Fig. 6, a sectional view of the feed device; Fig. 7, a section taken on the line xx of Fig. 5; and Fig. 8, a view in perspective, looking toward its outer side, of 20 the pawl.

The same letters denote the same parts.

As ratchet-drills have heretofore been constructed, the screw that takes up the feed is 25 permanently connected with the other parts of the mechanism. Neither the drill nor the wrench can be employed separately, and in use 30 the parts are apt to bind so tightly as to interfere with the proper operation of the tool, and to require the feed-screw to be turned back 35 and the drill to be loosened in its bearing. By means of the present improvement this objection is obviated, the feed-screw and holder being so combined with the wrench that the working of either part is not interfered with, and, 40 when desired, the drill mechanism can be laid aside and the wrench used as such for the various purposes a ratchet-wrench is ordinarily applied to.

In the drawings, A represents the frame or 45 body of the device, having the wrench B, the wrench-holder C, the ratchet D, the pawl E, and the handle F. The drill G is held in the wrench B, its upper end projecting through 50 the wrench and engaging in the socket h in the feed-screw H. The latter is held and engages in a nut, I, which in turn is contained in a frame or holder, J, consisting of the caps j j' , connected by the bars j^2 , and having a square pin, K, extending from the outer head, j , 55 through the nut and into a perforation, h' , of corresponding shape within the screw H. The

nut I is perforated at i to receive a turning-lever indicated by the dotted lines L, Figs. 6, 7. The nut may be furnished with a ring, i' , which, engaging in a corresponding groove in the cap j , serves to guide the movement of the nut more steadily in the holder J. The nut I is made to turn freely upon the pin K, the perforation in the nut being of sufficient size therefor. The pin prevents the screw H from rotating with the nut, and as the latter is turned the screw is moved longitudinally on the pin. The holder J in use is supported at its outer end in the usual manner, and as the drill-point is advanced by the wrench the screw H is kept 60 against the head of the drill by suitably working the nut I with the lever L. Although the holder J, the wrench A, and drill G are combined to effect the drilling, the working of either the wrench or the drill-holder is free of the 65 strains imposed upon the other, and to use the wrench by itself the drill-holder has merely to be laid aside.

The improvement further relates to the means used in fastening the wrench proper, B, in the 70 holder C. This is accomplished by means of the plate M, which is pivoted to the handle F at m , and extends thence over upon the ratchet D, being at that end shaped to encircle the projection b of the wrench B, but preferably 75 not to wholly encircle the projection b , leaving a space, b' , upon the ratchet D, to enable the operator to clasp the ratchet with his thumb and keep the ratchet from turning back as the wrench-handle is turned back for another move- 80 ment of the wrench, as the nut or other thing being turned by the wrench is apt, when loose, to follow the movement of the handle. The plate M is, however, extended far enough for its arms m m' to bear upon the wrench at op- 85 posite sides thereof, and upon the side of the ratchet, and hold the wrench evenly in the holder, and but for the arms m m' bearing against the side of the ratchet the wrench, when turned with the ratchet side downward, 90 would drop out of the holder C. The plate is furnished with a tongue, m^2 , which fits into a recess, m^3 , in the handle F, and by means of a screw, m^4 , passing into the handle F, and the perforation m^5 in the tongue, the plate can be 95 fastened down upon the wrench. To detach the wrench B from the holder C the screw m^4 100

is disengaged from the tongue m^2 and the plate M turned up, as in Figs. 3 and 4, leaving the wrench free to be withdrawn from the holder C. The pawl E, upon its outer side, is furnished with a projection, e, which engages loosely in a recess, m^6 , in the plate M, and operates to hold the pawl in its seat when the tooth of the pawl is withdrawn from the ratchet D. This I find to be better than perforating the pawl and hanging it on a pin, as in constructions previously patented.

I claim—

1. The combination of the wrench B, drill G, screw H, and holder J, having the heads

j, j' , bars j^2 , pin K, and perforated nut I, said 15 holder and screw being detachable from the drill and wrench, substantially as described.

2. The combination of the handle F, plate M, having the perforated tongue m^2 , the recess m^6 , and arms $m^1 m'$, the pawl E, having the 20 projection e, the screw m^4 , the holder C, wrench B, and ratchet C, substantially as described.

Witness my hand.

JOHN A. MILLER.
